UNITED STATES PATENT OFFICE.

JOHN H. MILLER, OF MACDUNN, WEST VIRGINIA.

CAR-CONTROLLED TROLLEY-LINE CUT-OUT.

Application filed October 5, 1922. Serial No. 592,660.

To all whom it may concern:

Be it known that JOHN H. MILLER, a citizen of the United States of America, residing at MacDunn, in the county of Fayette and State of West Virginia, has invented new and useful Improvements in Car-Controlled Trolley-Line Cut-Outs, of which the following is a specification.

In mine tracks where a branch track leaves the main track, the trolley wire suspended above the latter must cross the main track to provide means for a mine car taking the branch track. This spanning section of the trolley wire constitutes a hazard to the lives of humans and animals passing down the main track who must pass beneath this section of trolley wire. It is a common practice to shield this in some manner or other and ordinarily by means of depending wooden guards disposed on opposite sides of the crossing section of trolley wire. These are not effective for the purpose intended, however, for the reason that they rot or become damaged as a result of impact with something carried in the passing train. It is the purpose of the present invention to so construct the trolley wire for the branch track as to make that section spanning the main track normally dead or inactive, energizing it, however, from the main trolley wire through an interposed car controlled cut-out, so that as the train takes the branch track, the normally dead section is rendered active or alive for the operation of the motor propelling the passing train.

In the construction illustrated, a specific embodiment has been adhered to, but to this the invention is not to be restricted further than is prescribed in the annexed claims.

In the accompanying drawings;

Figure 1 is a plan view of a section of mine track and connected branch track showing the invention operatively applied thereto.

Figure 2 is a side elevational view of the toggle joint tread element by means of which the car is enabled to actuate the cut-out.

Figure 3 is a section on the line 3—3 of Figure 2.

Figure 4 is a perspective view of the toggle joint tread element.

Figure 5 is a detail elevational view of the cut-out and adjacent operating means therefor.

Figure 6 is a front elevational view of the cut-out looking at the same from the plane indicated by the line 6—6 of Figure 5.

The main trolley wire 10, as is usual in practice, is disposed adjacent the side wall 11 of the mine and to the side of the main track 12 with which the branch track 13 is connected, the trolley wire 14 of the latter having a normally dead section 15 spanning the main track and tensioned between insulators 16. This section 15 of the trolley wire is normally dead but is designed to be energized from the main trolley wire 10 by means of a feeder 17 extending from the trolley wire 10 to the cut out 18 and a feeder 19 extending from the cut-out 18 to the normally dead section 15, as clearly shown in Figure 1. The branch track trolley wire is energized from the main trolley wire 10 by a feeder or connection 20. In the illustrated embodiment, a single trolley is shown, the track being the return conductor, but the invention is equally applicable to a double trolley system. When the cut-out 18 is closed, the section 15 of the trolley wire is energized from the main trolley wire through the feeders 17 and 19, so that a train in passing from the main track to the branch track will have its motor or driving means continuously energized.

The cut-out 18 is designed for actuation by the passing car, the cut-out being held normally in open position and constituting a knife switch of which the blade 21 has its handle portion engaged by a clip 22 exterior to an insulating bushing 23, the clip being connected by means of a link 24 with the upper end of the arm 25 of a rock shaft 26. The rock shaft is mounted in bearings 27 secured to one of the ties 28 by means of appropriate bolts, that portion of the shaft between the bearings being encircled by a spiral spring 29, one end of the spring having bearing contact as at 30 on the upper face of the tie and the remaining end being connected to the shaft as at 31. Closing movement of the switch blade 21 effects a torsional strain on the spring, so that when the force tending to rock the shaft 26 is removed, the spring operates to rotate the shaft and thus move the switch blade to open position.

A knife switch is employed in the present instance as constituting the cheapest and one of the most acceptable forms of cut-outs but obviously any source of cut-out,

dependent in its operation on reciprocatory movement, will serve the purpose of the invention.

Switch closing movement is imparted to the rock shaft by means of a toggle joint tread element generally indicated by the numeral 32, as shown clearly in Figure 4. This element consists of the complemental cross-sectionally L-shaped plates 33, the vertical flanges of which are formed with ears 34 by which the plates are pivotally connected together. The horizontal flanges or tread flanges of the plates 33 are extended beyond the vertical flanges at the ends opposite the pivot point and are offset as shown to provide ears 35 formed with elongated slots 36, these slots engaging pins or studs 37 set in the ties. The rock shaft at the end opposite the arm 25 carries a second arm 38 having a link connection 39 with the pivotal connection between the plates 33. When the rock shaft is in a position in which the cut-out is open, the arm 38 is disposed so as to raise the blades 33 at their pivotal point and the longitudinal movement of the plates which must take place in this operation is provided for in the slotted connections 36. The outer ends of the blades are, therefore, disposed below the upper face of the track rail tread and the horizontal or tread flanges are adapted for engagement by the car wheel flanges on passing on to the branch track. In their normal position, in which the cut-out is open, the flanges 33 are inclined upwardly to the point of their pivotal connection and the car wheel flange may, therefore, engage them easily at the lower points adjacent the ears 35. When the flange has reached the pivotal connection of the plates, they are depressed their full depth and the rock shaft is moved the necessary distance to throw the switch blade 21 into engagement with its clips, thus establishing connection between the main trolley wire 10 and the normally dead section 15 and providing for the operation of the motor of the train passing on to the branch track.

Having described the invention, what is claimed as new and useful is:—

50. 1. The combination with the main and branch tracks of a mine, each having a trolley conductor disposed above and to one side thereof, of a normally dead section of trolley conductor interposed in the conductor of the branch track, and car controlled connections between the main trolley conductor and the normally dead section.

60. 2. The combination with the main and branch tracks of a mine, each having a trolley conductor disposed above and to one side thereof, of a normally dead section of trolley conductor interposed in the conductor of the branch track, conductors connecting the main trolley conductor with the normally dead section, a cut-out interposed

between said conductors, and car controlled actuating means for said cut-out disposed adjacent one rail of the branch track and operable by the flange of a wheel of a passing train.

70. 3. The combination with the main and branch tracks of a mine, each having a trolley conductor disposed above and to one side thereof, of a normally dead section of trolley conductor interposed in the conductor of the branch track, conductors connecting the main trolley conductor with the normally dead section of conductor, a cut-out interposed between said conductors, a rock shaft provided with an arm operatively connected with said cut-out, and car actuated means for operating said rock shaft.

75. 4. The combination with the main and branch tracks of a mine, each having a trolley conductor disposed above and to one side thereof, of a normally dead section of trolley conductor interposed in the conductor of the branch track, conductors connecting the main trolley conductor with the aforesaid normally dead section of conductor, a cut-out interposed between said conductors, a rock shaft, a spring surrounding said rock shaft and tending to hold same in a position where said cut-out is open, and car actuated means for rocking said rock shaft in opposition to the torsion of said spring.

80. 5. The combination with the main and branch tracks of a mine, each having a trolley conductor disposed above and to one side thereof, of a normally dead section of trolley conductor interposed in the conductor of the branch track, conductors connecting the main trolley conductor with the normally dead section, a cut-out controlling said conductors, a rock shaft operatively connected with said cut-out, and a toggle joint operating element disposed adjacent said track and adapted for contact with the flange of a car wheel to actuate said rock shaft.

85. 6. The combination with the main and branch tracks of a mine, each having a trolley conductor disposed above and to one side thereof, of a normally dead section of trolley conductor interposed in the conductor of the branch track, conductors connecting the main trolley conductor with the normally dead section or conductor, a cut-out controlling said conductors, a toggle joint operating element comprising a pair of pivotally connected plates disposed adjacent one rail of said branch track and adapted for contact with the flange of a car wheel, a rock shaft operatively connected with said cut-out, and operative connections between said rock shaft and the pivotal connection between the plates of said toggle joint operating element.

90. In testimony whereof he affixes his signature.

JOHN H. MILLER.
